SLUG CASTING MACHINE

Gustave Rapprich, West New York, N. J., assignor
to Mergenthaler Linotype Company, a corpora-
tion of New York

Application May 12, 1932, Serial No. 610,756

18 Claims. (Cl. 199—50)

This invention relates to slug casting machines, such as linotype machines of the general organization represented in United States Letters Patent No. 436,532, to O. Mergenthaler, wherein circulating matrices and expansible spacebands are released from their respective storage magazines and then assembled in line, the composed line transferred to a vertically movable transporter or so-called "first elevator" which presents it to

10 the face of a slotted mold, the mold filled with molten metal to form a slug or linotype against the composed line, and the matrices and spacebands thereafter returned through transfer and distributing mechanisms to the magazines from

15 which they started.

In these machines, the first elevator, in presenting the composed line to the mold, descends to its casting position by gravity and delivers the line between a pair of clamping members or vise 20 jaws which engage the opposite ends of the line to limit its endwise movement as the expansible spacebands are forced upwardly in effecting justification of the line. These vise jaws are adjustable toward and away from each other to vary 25 the space between them to accord with the length of the slot of the mold which is in use at the time.

It sometimes happens that the operator will compose an unjustified line of such length that it will not pass readily between the vise jaws, and 30 in such case the end matrix or matrices is or are liable to be displaced or lifted in the first elevator by frictional engagement with the jaws, even though the line actually enters the jaws, and as a result (since the operation of the machine continues) the displaced matrices are severely damaged when the mold is moved forwardly for the slug casting operation, and besides a serious metal squirt may occur.

The present invention overcomes these and 40 other difficulties, by preventing the casting operation whenever an overset or "tight" line is presented to the vise jaws. To this end, specifically, the right-hand vise jaw is provided with a line engaging portion which is adapted to be moved 45 downwardly and inwardly by the end matrix of an overset or tight line, whereby the space between the jaws is contracted or lessened, and the first elevator thereby arrested in its downward movement. Failure of the elevator to make a 50 complete descent brings into play the well known "vise automatic" which stops the machine before the casting operation takes place or before any damage can occur.

In the accompanying drawings, the invention 55 has been shown merely by way of example and

in preferred form, but obviously many variations and modifications may be made therein which will still be comprised within its spirit. It is to be understood, therefore, that the invention is not limited to any specific form or embodiment, 60 except insofar as such limitations are specified in the appended claims.

Referring to the drawings:

Fig. 1 is a front elevation, partly in section, 65 of a portion of a linotype machine embodying the present improvements, and showing certain parts of the line delivery and line clamping devices;

Fig. 2 is a detail elevation, showing the movable section of the right-hand vise jaw moved 70 downwardly and inwardly by the delivery of an overset line;

Fig. 3 is a similar view, partly broken away to reveal the interior construction, showing the movable section of the vise jaw in its upper or normal position; 75

Fig. 4 is a view like Fig. 2, but showing the movable section of the vise jaw as moved downwardly through frictional engagement with the end matrix of a tight line; 80

Fig. 5 is a top sectional view of the vise jaw taken on the line 5—5 of Fig. 4; and

Fig. 6 is an end elevation of the line engaging portion of the vise jaw.

In the normal operation of the machine, a line 85 of matrices X and spacebands Y is composed in an assembling elevator (not shown), by means of which it is lifted between the depending fingers a and a¹ of the line delivery slide A, and transferred thereby through the intermediate 90 channel B to the vertically movable transporter or first elevator C. The transporter thereupon descends to present the composed line to the face of a slotted mold (not shown), and between the opposed clamping members or vise jaws D and 95 E, which hold the line against endwise movement during the justifying and casting operations. In descending to casting position (by gravity), the line transporter engages and depresses the so-called "vise automatic" (not shown) which permits the cycle of operation of the machine to continue. 100

The left-hand clamping jaw D is adjustable toward and away from the right-hand jaw E to permit the jaws to be spaced apart a distance 105 corresponding to the length of the mold slot in which the slug is to be cast. At the time of justification, the adjustable left-hand jaw D is located and sustained against endwise movement in the position in which it is set, and it is sub- 110

sequently retracted sufficiently to relieve the composed line of pressure before the transporter rises after the casting operation. Such movements of the jaw D are controlled in the usual 5 way by the vertical reciprocating wedge F through the auxiliary grooved rod F¹ and the cooperating banking block F². The right-hand jaw E is relatively fixed and adapted to stand in line with the contiguous end wall of the mold slot when the 10 matrix line is expanded between the jaws.

So far as described, the construction of the parts and their mode of operation, except as hereinafter pointed out, are or may be the same as those embodied in the commercial linotype 15 machines, and will be readily understood by those skilled in the art.

In carrying out the present invention, the right-hand vise jaw E is divided vertically into two sections e and e¹. The section e is secured to the 20 vise frame in the usual manner, being relatively stationary, while the section e¹ is slidably attached to the section e by a T-head and slot connection, best illustrated in Fig. 5. As there shown, the section e is formed with a T-head e² adapted slidably 25 to fit within a correspondingly shaped recess e³ fashioned in the section e¹. It will be observed that the section e¹ comprises a main body section e⁴ and a plate e⁵ set back in the body portion and having its outer face flush with the front wall of 30 the vise jaw E, a portion of the plate e⁵ being fashioned to form one wall of the recess e³ into which the T-head e² is snugly but slidably fitted. The plate e⁵ is securely fastened to the body portion e⁴ in any desired manner, as by rivets R.

It will be noted that the side of the section e on which the T-head is formed presents three 35 guiding or bearing surfaces, namely, the top m of the T-head and the side shoulders n and o, against which corresponding surfaces of the recess e³ are 40 adapted to engage. Although this type of connection permits the section e¹ to move freely, it also prevents the section from rocking sidewise during its movement. Further to facilitate its operation, the section e¹ is cored out as at e⁶ and e⁷, whereby 45 it is lightened and balanced to lessen its frictional engagement with the surfaces of the section e against which it bears.

As already stated, the section e¹ of the vise jaw E is adapted to be moved downwardly and inwardly, and to this end the contiguous surfaces of the sections e and e¹ are formed obliquely, the 50 guiding surfaces m, n and o inclining from top to bottom toward the opposite vise jaw D. Thus, as the section e¹ is moved downwardly by pressure 55 acting upon it from directly above, it is cammed in the direction of the vise jaw D by the guiding surfaces just referred to.

The downward movement of the section e¹ is 60 against the pressure of a compression spring s, one end of which is seated in the section e, as at s¹, the other end being seated in the movable section e¹, at at s². The spring s tends normally to hold 65 the movable section e¹, in its raised position against a plate e⁸, which latter is secured to the section e by screws e⁹ and is adapted to overlie the connection between the two sections to limit the upward movement of the section e¹ and to keep dirt and foreign matter from entering and collecting between the sections, where its accumulation 70 would soon impair the easy movement of the section e¹. The plate e⁸ is detachably arranged in order to facilitate the attachment and removal of the section e¹ to and from its cooperating section e. A spring detent k is arranged in the upper part 75 of the movable section e¹ so as to project through

the line engaging face thereof for a purpose to be described later.

In the operation of the machine, when a line or proper length is delivered by the first elevator C to the vise clamping jaws D and E, it will enter 80 between the jaws without disturbance and the transporter upon reaching its casting position will depress the vise automatic and permit the cycle of operation of the machine to continue. However, when a line is overset or its length is greater 85 than the space between the vise jaws D and E, as shown in Fig. 1, the end matrix or matrices of the composed line will engage the shoulder e¹⁰ of the movable section e¹ and exert a downward pressure thereon, causing it to move downwardly 90 against the pressure of the compression spring s. Due to the fact that the guiding surfaces m, n, o of the section e are inclined, the section e¹ is cammed inwardly during its downward movement toward the opposite vise jaw D, thereby contracting or lessening the distance between the two 95 jaws D and E, so that when the section e¹ reaches the limit of its downward movement it is impossible for the composed line to be lowered between the jaws. Hence the first elevator C is 100 brought to rest before it reaches its casting position and therefore is prevented from actuating the vise automatic to permit the operation of the machine to continue. The machine is thus stopped automatically and no damage allowed to 105 occur.

In the event of a "tight" line, that is to say, a line which might ordinarily fit between the jaws D and E but which nevertheless would fit too 110 tightly to permit proper justification and alignment of the matrices, the end matrix engages the projecting end of the spring detent k as shown in Figs. 3 and 4, and the added frictional engagement thus afforded suffices to force the section e¹ downwardly and inwardly as in the case of an 115 overset line.

It may be added for the sake of clearness, that under the clamping pressure of the vise jaws during justification of a line of proper length the spring detent k is adapted to recede within the 120 cavity k¹ in which it is located. Thus the vise jaw E presents an even line engaging face and affords no opportunity for endwise tilting or mal-alinement of the line of matrices and spacebands.

Having thus described my invention, what I 125 claim is:

1. In a slug casting machine, the combination 130 of a pair of line clamping members, means for delivering a composed line to the clamping members, and means actuated by the delivery at different casting levels of an overset or tight line to the clamping members for lessening the space between them so as thereby to prevent their reception of the line.

2. In a slug casting machine, the combination 135 of a pair of clamping members adapted to be set in mutual spaced relation to receive between them a composed line of predetermined length, means for delivering the composed line to the clamping members, and means actuated by the delivery at different casting levels of a line of greater than the predetermined length to the clamping members to contract the space between them and thereby prevent their reception of the line.

3. In a slug casting machine, the combination 140 of a pair of line clamping jaws, a transporter for delivering a composed line to the clamping jaws, and means adapted to be actuated by the delivery at different casting levels of an overset or tight 145 line.

- line to the clamping jaws to lessen the space between them.
4. In a slug casting machine, the combination of a pair of line clamping jaws, and a vertically movable transporter for delivering a composed line to the clamping jaws, one of said jaws being movable relatively to the other by an overset or tight line to lessen the space between them. 80
5. In a slug casting machine, the combination of a pair of line clamping jaws, and a vertically movable transporter for delivering a composed line to the clamping jaws, one of said jaws being divided into sections, one of which is arranged to be moved inwardly when engaged by an overset or tight line as the latter is being delivered to the jaws, whereby the space between the jaws is lessened and their reception of the line prevented. 85
10. A combination as set forth in claim 9, wherein the means for increasing the frictional engagement of the line with the clamping jaw comprises a spring detent arranged in the movable clamping jaw so as to engage the composed line as the latter is being brought into a position between the jaws. 90
11. A combination as in claim 1, wherein the operation of the machine is automatically stopped by the lessening of the space between the line clamping members, as by the arrest of the line transporter. 95
12. A combination as in claim 4, wherein the jaw or jaw section moved by an overset or tight line is the right-hand jaw. 100
13. In or for a slug casting machine, a line clamping jaw formed in two sections slidably secured together so that one section is free to move vertically, a compression spring arranged between the two sections and adapted to resist the downward movement of the movable section, and means to limit the upward movement of said section. 105
14. In a slug casting machine, a line clamping jaw as described in claim 13, wherein the jaw is divided along an inclined plane so that during its downward movement a camming action will be imparted to the movable section by the contiguous guiding surface of the other section. 110
15. In a slug casting machine, a line clamping jaw as described in claim 13, wherein the two sections are secured together by a T-head and slot connection. 115
16. In a slug casting machine, a line clamping jaw as described in claim 13, wherein the means to limit the upward movement of the movable section comprises a detachable plate removable to permit the application and removal of the movable section to and from the other section. 120
17. In a slug casting machine, a line clamping jaw as described in claim 13, characterized by the fact that the movable section of the jaw is cored out to reduce and distribute its weight to produce a light balanced structure. 125
18. In a slug casting machine, a line clamping jaw as described in claim 13, characterized by the fact that it is the right-hand jaw of the machine. 130
